UNITED STATES PATENT OFFICE.

EDMUND KIKUT, OF BERLIN, GERMANY.

FLYING-MACHINE HAVING SUPPORTING-PLANES LOCATED ONE BEHIND ANOTHER.

1,058,983.

Specification of Letters Patent.

Patented Apr. 15, 1913

Application filed October 11, 1912. Serial No. 725,306.

To all whom it may concern.,

Be it known that I, EDMUND KIKUT, engineer, a subject of the German Emperor, residing at 54 Klopstockstrasse, Berlin, Germany, have invented new and useful Improvements in Flying-Machines Having Supporting-Planes Located One Behind Another, of which the following is a specification.

10 The invention relates to flying machines having supporting planes located one behind another.

The object of my invention is to render a downfall at the smallest angle impossible and simultaneously to impart great longitudinal stability to flying machines, which have two or more supporting planes located one behind another, of which the front plane has an exceedingly large angle of flight, say 25 about 14°, while the rear plane has a considerably smaller angle, say about 5°. I attain this end by locating the center of gravity of my machine about half the breadth and at least the third of the breadth of the 25 plane in front of the front edge of the rear plane and by arranging simultaneously the rudder plane in such a manner above or below the center of gravity of the flying machine, that the resultant of the wind pressure and elevating force acting on it in the changing position of its center of pressure passes approximately through the center of gravity of the flying machine.

One illustrating embodiment of my invention is represented by way of example in the accompanying drawing, wherein—

Figure 1 is an elevation showing one form of my improved flying machine, the center of gravity being located vertically above the 40 starting wheel, Fig. 2 is a top plan view thereof, and Fig. 3 is a diagram explained hereinafter.

Referring to the drawing, *a* designates the front supporting plane, having an exceedingly large angle, say about 14°, and *b* designates the rear supporting plane having a considerable smaller angle, say about 5°.

Tests have shown that the horizontal resistance increases approximately proportionally with the magnitude of the angle of flight, while the elevating force at first likewise increases fairly proportionally with the magnitude of the angle of flight, as is shown in the diagram of Fig. 3 of the accompanying drawing, but increases only inconsiderably above a certain limiting angle, say

about 10°. If the plane is greatly curved, the elevating force remains fairly constant from this point onward without regard to the magnitude of the angle of flight up to another limiting angle about 20°, after which the elevating force of the plane rapidly decreases as the angle increases. An arrangement is known, where this fact is used for steadyng the flying machine longitudinally, the front plane being given such a great angle, that when the machine fluctuates about a few degrees, its elevating force remains practically constant, while the rear supporting plane has an angle of flight located on that portion of curve, in which the elevating force varies proportionally to the magnitude of the angle. The ratio between elevating force and resistance of the front plane being far more unfavorable as that resulting of the smaller angles used heretofore and especially as this machine is being steered by turning the entire machine, that is to say by increasing or decreasing the angle of flight of the front and back planes at the same time and in the same degree, the elevating force of the front plane remaining however unchanged, only the resistance increasing during that process, the front plane of the known machine is made very small in comparison to the back one, this being done by placing the center of gravity of the machine on the back plane itself or immediately in front of the front edge of the same.

Now the first object of my invention is to locate the center of gravity of my machine nearly half the breadth of the plane in front of the rear plane for the following reasons: Whereas the elevating force and the position of the center of pressure of the front supporting plane remains approximately constant when the angle of flight decreases, the elevating force of the rear plane, which has a materially smaller angle, rapidly decreases and the center of pressure travels toward the rear edge of the supporting plane. In order that the longitudinal stability may be automatic, it is, however, necessary, for this special case, that the product of the diminishing elevating force and its increasing leverage measured from the center of gravity of the machine shall become always considerably smaller as the angle of flight decreases in order that the approximately constant turning moment of the front supporting plane can lift the end of the ap-

paratus for the purpose of restoring the normal angle of flight.

Another object of my invention is a new way of steering the machine.

- 5 Flying machines comprising supporting planes arranged one behind another were heretofore steered by means of an adjustable steering plane or rudder arranged a long distance in front of the center of gravity of the machine. Sudden changes of direction of the wind change the elevating force of this rudder plane and thereby the turning moment of the front portion of the machine, whereas in the machine according to my invention the front turning moment must remain as constant as possible for obtaining automatic longitudinal steadyng; in addition, in my improved machine, when the machine turns and raises the fore end, as 10 already mentioned, only the resistance of the front supporting plane would increase, as at angles of flight between 10° and 20° the resistance of the air increases without the elevating power increasing.
- 15 Having regard to the above-mentioned circumstances, according to my invention the rudder plane is arranged in such manner above or below the center of gravity of the flying machine that the resultant of the wind pressure and elevating force acting on it in the changing positions of its center of pressure passes approximately through the center of gravity of the flying machine. The resultant force has then only very in- 20 significant or no influence at all on the inclination of the flying machine and on the angle of flight of the fixed planes *a* and *b*. If the angle of inclination of the rudder plane *c* is varied, the entire flying machine 25 ascends and descends while maintaining its inclination, that is without turning relatively to the direction of flight at the time. The rudder plane is turned by means of any desired adjusting mechanism *d*, either its 30 entire surface being turned or only its rear portion which, as shown, is attached by means of hinges to the front fixedly mounted part; in the latter case the curvature of the rudder plane is altered simultaneously 35 with the angle of flight, and the pilot is able to vary the elevating force of the rudder plane. The elevating force on the fixed supporting planes *a* and *b* thus remains constant when actuating the horizontal rudder, 40 and the flying machine is caused to ascend and descend solely by increasing or diminishing the elevating force on the rudder plane *c* which, accordingly and in contradistinction to rudder planes used heretofore, 45 has the character of a supplementary supporting plane.
- 50 By making the plane *c* very large it can be

used for carrying a considerable part of the lead and the fixed supporting planes *a* and *b* may be made correspondingly smaller. As 55 the longitudinal stability is greater, however, the greater the fixed planes *a* and *b* are, the fixed supporting planes are preferably made so large that they carry almost the total lead. When flying horizontally, when 60 the rudder plane *c* is adjusted to a small angle of flight, this plane will be subjected to only a small elevating force. If it is entirely relieved from this force, by correspondingly diminishing the angle of flight 65 of the plane *c*, the machine will only descend slowly. A rapid descent can be caused by giving the rudder plane a negative angle and thus causing the wind to act on the top of it. In the former case no material in- 70 crease in the velocity of travel will occur in consequence of the slow descent, while in the second case the velocity of travel actually becomes smaller as the resistance of the planes does not decrease with the decrease of 75 the total elevating force as in other machines, but, on the contrary, increases, and dissipates the kinetic energy which collects in consequence of the descent.

The flying machine cannot be fractured 80 owing to its being subjected to excessive stresses in consequence of the kinetic energy due to the rapid descent, and also a fall at a dangerous speed in consequence of the horizontal rudder being incorrectly positioned 85 cannot take place.

What I claim as my invention and desire to secure by Letters Patent is:

In a flying machine, the combination with the frame, of two supporting planes fixedly 100 mounted one behind the other thereon, the angle of flight of the front plane being a few degrees greater than that angle which corresponds to the approximate limit of proportionality between elevating force and magnitude of angle, the angle of flight of the rear plane being less than that of the front plane, but still within the approximate curve of proportionality between elevating force and magnitude of angle; the center of 105 gravity of the flying machine being located about half the breadth and at least a third of the breadth of the plane in front of the front edge of the rear plane, an auxiliary adjustable plane over the center of gravity 110 and means for adjusting the angle of flight of the auxiliary plane.

In testimony whereof I have signed my name to this specification in the presence of two subscribing witnesses.

EDMUND KIKUT.
